UNITED STATES PATENT OFFICE.

KARL FARKAS, OF GLEN RIDGE, NEW JERSEY.

INCANDESCENT LAMP WITH DRAWN-METAL-WIRE FILAMENT.

1,008,809.

Specification of Letters Patent. Patented Nov. 14, 1911.

Application filed June 23, 1911. Serial No. 635,012.

To all whom it may concern:

Be it known that J. KARL FARKAS, a citizen of the Kingdom of Hungary, and a resident of Glen Ridge, county of Essex, and 5 State of New Jersey, have invented certain new and useful Improvements in Incandescent Lamps with Drawn-Metal-Wire Filaments, of which the following is a specification.

This invention has reference to improvements in metal filament lamps and pertains particularly to that type of lamps which are provided with drawn metal wire filaments as an incandescent. Such drawn metal wire 15 filament may consist of one continuous piece of fine wire which is wound successively and alternately over the insulated supports or anchors near the ends of the glass rod within the lamp and connected with its ends to the two leads. This arrangement however is defective owing to the longitudinal expansion of the fine metal wire during the operation of the lamp. When this fine wire is heated to incandescence it expands 20 throughout its entire length to such a degree as to be undesirable or impracticable. It is self-evident that the longitudinal expansion of such a fine relatively long wire arranged in a rather limited space and passing from 25 anchor to anchor down to the leads where its ends are permanently secured is such as to bulge out the single sections of the wire and press them too hard against the inner walls of the anchor loops.

It is the special purpose of this invention to avoid the above described deficiencies of a drawn metal wire lamp and still retain the good qualities of same without increasing the cost of their manufacture. This has 40 been primarily attained by dividing the wire length into two portions which has been rendered possible for practical purposes by the construction of a novel interior stem with a rod or arbor provided with a conductive means in the lower portion of the rod whereby such division is effected. Accordingly there are two wire lengths within one lamp and the longitudinal expansion has been reduced to one half which answers 45 the practical requirements in the manufacture of lamps with drawn metal wire filaments while the costly cementing of the single hair pin loops of the former metallic filament lamps is also avoided.

In order to make the invention entirely

clear reference is made to the accompanying drawing in which:—

Figure 1 represents in elevation a lamp with drawn metal wire filament embodying in desirable form the present improvements. 60 Fig. 2 shows in top plan view the upper part of the rod or arbor, Fig. 3 is a like top plan view of the lower portion of said rod or arbor, and Fig. 4 illustrates in elevation somewhat in perspective view the lower portion 65 of the interior stem on an enlarged scale.

Similar characters of reference denote like parts in all the figures.

In the drawing in Fig. 1 *a* represents the lamp globe, *b* is the interior stem, *c* the rod or arbor, *d* the drawn wire filament of a refractory metal and *e* the lamp socket. The lamp is made, exhausted and finished in the same manner as other lamps having drawn wire filaments of a refractory metal such as 70 tungsten for instance. The fine drawn metal wire filament however consists of two sections for the reasons above stated. In order to render possible the continuous passage of the current through both portions of the filament the novel glass stem with rod shown in detail in Fig. 4 on an enlarged scale is provided. The hollow stem proper *b* has the usual solid glass portion *b*¹ through which 75 the leads *f* pass. The rod or arbor *c* made of glass as usual is fused to the top portion *b*¹ of the stem *b*. A rim *c*¹ is formed on the rod *c* right above the solid portion *b*¹ of the stem *b*. The rim *c*¹ supports a plurality of 80 anchors *g* of even number which are insulated by the glass of the rim *c*¹ and merely 85 act as mechanical supports for the single sections of the drawn metal wire filament *d*. A like rim *i* at the top of the rod supports a 90 corresponding number of insulated anchors *g*¹ plus two, acting also solely as mechanical supports. 95

In order to divide the continuous filament into two portions the horizontal auxiliary lead *h* is fused into the rim *c*¹ as shown. 100 This lead is preferably straight and has two free ends so that there are now four free ends for the four free ends of the two portions of the drawn wire filament, the two other free ends being the leads proper *j*, *f*. 105 The one portion of the drawn wire filament starts at one lead *f* and passes successively and alternately over three top anchors, two bottom anchors and is secured to the one free end of the auxiliary lead. The current then 110

may pass through the auxiliary lead into the second portion of the drawn wire filament whose one end is secured to the second end of said auxiliary lead. This second portion also passes over three top anchors and two bottom anchors while its second free end connects with the second lead proper thereby completing the circuit.

In the described manner the longitudinal expansion of the filament is reduced to one half in accordance with the division of the long drawn wire filament into two portions preferably of equal length while the costly cementing of the single hair pin loops is rendered unnecessary and the deformation of the expanding filament is reduced to a practically permissible degree, leaving the single loops of each portion practically straight during use. As above described and shown each portion of the drawn wire filament consists of three loops. However any even number of loops with necessary anchors may be provided according to requirement.

25 I claim as my invention:—

1. An incandescent lamp with drawn metal wire filament divided into two portions comprising an interior stem with leads and rod, a rim on said rod near the stem, an auxiliary lead in said rim, a plurality of insulated anchors secured therein, and a corresponding number of anchors plus two secured to the top of the rod.

2. A metal wire filament lamp comprising an interior stem with leads and rod, a rim on said rod near the stem, an auxiliary lead in said rim, a plurality of insulated anchors secured therein, and a metal wire filament composed of two portions and supported by the anchors, each portion being connected with one end to one lead proper and with the other to one end of the auxiliary lead.

3. A tungsten wire filament lamp comprising an interior stem with leads and rod, a rim on said rod near the stem, an auxiliary lead in said rim to effect a division of the filament into two portions, a plurality of

insulated anchors secured therein, and a corresponding number of anchors plus two secured to the top of the rod to connect with 50 the ends of the auxiliary lead.

4. A tungsten wire filament lamp comprising an interior stem with leads and rod, a rim on said rod near the stem, an auxiliary lead in said rim, a plurality of insulated anchors secured therein, and a drawn metal wire filament composed of two portions and supported by the anchors, each portion being connected with one end to one lead proper and with the other to one end of the 60 auxiliary lead.

5. In a tungsten wire filament lamp having a stem with leads, a glass rod or arbor fused to the stem, a rim on said rod near the stem, an auxiliary lead in said rim, a 65 plurality of insulated anchors secured therein, a rim at the top of the rod, and a plurality of anchors of like number plus two secured to said top rim of the rod.

6. In a tungsten wire filament lamp having a stem with leads and a rod fused thereto with a rim in its bottom and top portions, a horizontal auxiliary conductive lead in the bottom rim, a plurality of insulated anchors of even number therein, a plurality 75 of insulated anchors plus two in the top rim, and a metal wire filament composed of two portions, the one portion being connected with one end to one lead then passing over half the number of the top and bottom 80 anchors and connecting with its second end to one end of the auxiliary lead, the second portion being connected with one end to the second end of the auxiliary lead then passing over the remaining top and bottom 85 anchors and connecting with its second end to the second lead, thereby completing the circuit.

Signed at New York, N. Y., this 22nd day of June, 1911.

KARL FARKAS.
